UNITED STATES PATENT OFFICE.

CHARLES DE MINICO, OF PORTSMOUTH, OHIO, ASSIGNOR TO UNITED SHOE MACHINERY COMPANY, OF PATERSON, NEW JERSEY, A CORPORATION OF NEW JERSEY.

LASTING-MACHINE.

1,111,826.

Specification of Letters Patent. Patented Sept. 29, 1914.

Application filed August 18, 1909. Serial No. 513,453.

To all whom it may concern:

Be it known that I, CHARLES DE MINICO, a citizen of the United States, residing at Portsmouth, in the county of Scioto and State of Ohio, have invented certain Improvements in Lasting-Machines, of which the following description, in connection with the accompanying drawings, is a specification, like reference characters on the drawings indicating like parts in the several figures.

This invention relates to lasting and nailing machines and is herein shown as embodied in a machine of the type shown in United States Letters Patent No. 584,744, granted June 15, 1897.

An object of the present invention is to provide means for effecting adjustments to control the angular relation of the plane of the shoe bottom to the several instrumentalities of the machine. A particular condition rendering this adjustment desirable is found in connection with the nailing instrumentalities. Experience has demonstrated that in lasting shoes certain angular relations of the plane of the shoe bottom to the direction of the nails or tacks is desirable by which the tacks are driven at an oblique angle to the plane of the tack receiving surface of the shoe. The angular relation of the plane to the machine is determined by the vertical position of the shoe bottom rest because the vertical position of the edge of the shoe is determined by the tack holder. Many modern lasts, however, particularly women's lasts, are rounded or arched at the shanks while they are flat at the ball and toe. This throws the shoe out of proper angular relation to the driver at the shank so that the tacks are inserted at too great an angle to the plane of the shoe bottom and sometimes these tacks fail to hold the upper securely.

An important feature of this invention consists in the combination with tack inserting mechanism and shoe guiding devices, of means under control of the workman to adjust said devices and mechanism relatively to control the angular relation of the tack receiving face of the shoe to the ingoing tack. This improvement may be employed to cause tacks to be inserted in the same angular relation to the receiving face of portions of the shoe differing from one another

as do the shank and forepart of the lasts mentioned, or it may be employed to cause insertion of tacks in different angular directions in different portions of the shoe as will be readily understood. As herein shown, the shoe bottom rest is adjusted and it will be obvious that the adjustment of the rest takes place with relation to all the instrumentalities of the machine which have a definite position or path of movement and particularly with relation to the direction of advance of the wiper and the path of the grippers. Preferably means is provided for making definite degrees of adjustment and for securing the rest in adjusted position and the adjusting means is arranged so that it can be operated without interrupting the running of the machine. In the machine of the patent the bottom rest is a bar occupying an inclined relation to the direction in which the fastenings are inserted and one convenient way to adjust it for the purpose stated, is to shift it endwise in an inclined guideway although it may also be moved vertically as is also shown in the accompanying drawings.

The foregoing and other features of the invention including certain combinations of parts and more important details of construction will appear more fully in connection with the following description of the illustrated embodiment of the invention and will then be pointed out in the claims.

Figure 1 is a side elevation of a portion of said lasting and nailing machine equipped with the present invention; Fig. 2 is a vertical longitudinal section; Fig. 2^a shows another position; Fig. 3 shows in full and dotted lines the two positions of the bottom rest with relation to the other instrumentalities of the machine while the shank and the toe, respectively, of the shoe are being lasted; Fig. 4 is a modification in side elevation; Fig. 5 shows a further modification in vertical longitudinal section on line 5—5 of Fig. 6, and Fig. 6 shows the same in vertical transverse section.

The grippers 2 for pulling the upper, the combined tack block and wiper 4 for laying the upper down upon the shoe bottom and presenting a tack in position to be driven to fasten the upper, the driver 5 and its actuating mechanism, and the edge guide 6 may be substantially as shown in said prior

patent and the machine is provided with a bracket 10 to hold the bottom rest 12 which is used for positioning the shoe vertically.

In the construction shown in the main figures, the rear or left hand portion of the shoe rest has an endwise sliding engagement in a vertically inclined guideway in the bracket 10 to permit the shifting of the rest for vertical and horizontal adjustment. A latch 14 is pivoted to the bracket 10 at 15 and has a depending lug 16 adapted to drop down behind the rear end or cross-bar 13 of the bottom rest and hold the latter in its advanced position, that is, toward the right 15 in the drawings. For releasing this latch to permit the bottom rest to be adjusted toward the left in the inclined guideway for raising its shoe engaging end, a lifter 20 is pivoted to the rest at 21 and has an arm 20 22 extending rearwardly under the latch to raise the latch into the position shown in Fig. 2 against the tension of a spring 23 located in a socket in the bracket as shown best in Fig. 2. A swinging arm 25 pivoted 25 at its upper end as in Fig. 1 has a sliding pin and slot lifter raising and rest sliding connection at 26 with the latch lifter 20 and this swinging arm is connected by a rod 30, see Fig. 1, with a rotatable block 32 30 which is pivoted on a vertical rod 34 and has an eccentric stud 35 to which the rod 30 is fastened. The block 32 has an arm 36 by which it may be turned freely upon the rod 34 to move the eccentrically located stud 35 and thereby, through the rod 30, actuate the swinging arm 25.

Assuming the parts to be in the positions shown in Fig. 2 with the bottom rest retracted toward the left, a movement of the 40 swinging arm 25 toward the right will act through the lifting device 20 and the pivot pin 21 to slide the bottom rest toward the right. When the bottom rest has moved to the right far enough the projections 16 of the latch 14 will drop down behind the rear cross-bar 13 of the bottom rest and hold the rest against retraction. When it is desired to move the rest to the left, the lever 36 45 and connected parts will be reversely actuated and the swinging arm will turn the lifting device 20 about the pivot pin to lift the projection 16 of the latch from behind the cross bar 13. Continued movement of the swinging arm to the left will then transmit movement through the lifting device to the bottom rest for sliding it toward the left.

In Fig. 4 a slightly different construction is illustrated in which the latch 141 is rigidly fastened on the swinging arm 25 and has a beveled end on its depending arm which wedges the bottom rest 12 forwardly when the arm 25 is pulled to the right as shown in dotted lines. The arm 25 is connected 60 to the rest 12 by the pivoted lifter 20

through which it pushes the rest to the left as it does in the main figures.

In the constructions above described the bottom rest receives an adjustment both vertically and horizontally which may be particularly desirable when it is advantageous to have the rest engage the shoe bottom at different distances from the edge of the shoe. By varying the inclination of the guideway in the bracket through which it is adjusted 70 the movement may be made more or less vertical or horizontal or it may be made altogether horizontal and in Figs. 5 and 6 a modification of the adjusting mechanism is shown by which the movement given to the bottom rest is vertical. In this arrangement the guide for the rest is formed by one side of the bracket 10 which is embraced by lips 40 of a vertical arm 43 which carries the bottom rest 12. A bolt 42, extends 80 loosely through a slot in the bracket and into the arm 43 to confine the arm and rest in place. By varying the direction of the guiding faces and the slot in the bracket the direction of adjustment can be changed. 85 The adjustment is effected by a pin 44 which extends from the arm 43 into an oblique slot or groove 45 in the left hand end of the rod 30 which, for this purpose, is movable endwise in the bracket 10. Horizontal movement of the rod 30 effects, in an obvious manner, the vertical adjustment of the bottom rest and the end portions of the slot 45 are formed straight so that they hold the rest in adjusted position against upward 90 pressure from the shoe.

The block 32 is provided with a clamping screw by which it can be fastened to the vertical rod 34 if desired. This rod has also fast upon it a block 38 which is operatively connected to the tack supplying mechanism for shifting the latter to change the kind of tacks and also this vertical rod is connected with means to control the length of the tack inserting movement of the driver 105 all as fully explained in said United States Letters Patent No. 584,744. When the rest shifting block 32 is fastened to the rod 34 the rest and the tacking mechanism are simultaneously adjusted.

Having explained the nature and object of this invention and described a mechanism embodying it so that it can be used by others, I claim as new and desire to secure by Letters Patent of the United States: 110

1. A machine of the class described, having, in combination, means for inserting tacks into work sustained in the hands of the operator, work guiding means for determining the angular relation of the tack receiving 115 face of the work to the direction of the incoming tack, and means arranged for actuation to effect simultaneously, while the machine is running and the operator is so sustaining a shoe, both vertical and horizontal 120 125 130

components of an adjustment of an element of the guiding means for changing said angular relation.

2. A machine of the class described having, in combination, means for inserting tacks into work sustained in the hands of the operator, guiding means including a member extending obliquely with relation to and into engagement with the tack receiving face of the work for determining the angular relation of said face to the ingoing tack, and means under the control of the operator for adjusting said engaging member longitudinally toward and from the tack inserting means in said oblique direction whereby the angular relation of the face of the work to the direction of the ingoing tack is changed.

3. A machine of the class described having, in combination, means for working an upper over a last, means for fastening the upper, a shoe bottom rest having two predetermined operative positions in which it resists upward and outward movement of the shoe, supporting means in which the rest is slidable between such positions, and means for automatically locking the rest against displacement by pressure of the work against it while in either of said two operative positions.

4. A lasting machine having a reciprocating wiper constructed and arranged for movement inwardly over the shoe bottom to force the upper into lasted position, a bottom rest for determining the angular relation of the shoe bottom to the direction of movement of said reciprocating wiper, and a single means under control of the operator for effecting a simultaneous downward and inward adjustment of the rest toward the plane of the acting face of the wiper or reversely to change said angular relation of the plane of the sole to the direction of movement of the wiper.

5. A lasting machine having, in combination, a shoe bottom rest, means for effecting adjustment of the rest into one or another of a plurality of operative positions while the machine is in operation, and automatic means for positively locking the rest in adjusted position.

6. A machine of the class described, having, in combination, means for working an upper over a last, means for fastening the upper, an obliquely mounted bottom rest arranged to determine the plane in which the shoe bottom is presented, and means for adjusting the rest longitudinally into one or another of a plurality of operative positions to change that plane, said machine having provision for automatically locking the rest in adjusted position.

7. A machine of the class described, having in combination, a work rest mounted for longitudinal reciprocation between two posi-

tions, means for locking the rest when in its forward position, and means for actuating the locking means to release the rest and then by continued movement in the same direction to shift the rest.

8. A machine of the class described, having in combination, a support, a rest 12 mounted to slide forwardly and rearwardly in said support at an oblique angle to the plane of the wiper, a latch 14 pivoted to the support and adapted to engage behind the rest when in its forward position, a lifter 20 pivoted to the rest and a lever for operating the lifter to raise the latch and move the rest rearwardly.

9. A lasting machine, having, in combination, grippers, a rest or abutment for the shoe bottom, means under control of the operator for adjusting the rest substantially perpendicularly to the plane of the shoe bottom, into either of two predetermined operative positions and means for automatically locking the rest against displacement by the work while it is in either of its adjusted positions.

10. A lasting machine, having, in combination, devices for working an upper into lasted position and inserting tacks, a shoe bottom rest, and means under control of the operator for adjusting the rest and the tack inserting mechanism together.

11. A machine of the class described, having, in combination, mechanism adapted to supply and insert tacks of different kinds, a bottom rest for positioning the work, and means for simultaneously adjusting the rest and changing the kind of tacks supplied.

12. A machine for working an upper over a last and securing it, having, in combination, bottom engaging means for positioning the shoe, means for applying different kinds of fastenings, and means for changing the kind of fastenings and adjusting the shoe positioning means.

13. A lasting machine having, in combination, devices for operating on a shoe and shoe positioning means including a sole rest shiftable into a plurality of operative positions, means for holding the rest in an operative position, and operating means arranged to first release the holding means and then to effect movement of the rest.

14. A lasting machine having, in combination, devices for operating on a shoe and shoe positioning means including a sole rest shiftable into a plurality of operative positions, rest latching means, and operating means operatively connected with the latching means and with the rest for the purpose described.

15. A lasting machine having, in combination, devices for operating on a shoe and shoe positioning means including a sole rest shiftable into a plurality of operative positions, a latch 14, a latch lifter 20, and oper-

ating means 25 operatively connected with said lifter and with the rest to effect lifting of the latch and then retraction of the rest upon movement in one direction and 5 upon reverse movement to advance the rest and then allow the latch to become operative.

16. A lasting machine having, in combination, devices for operating on a shoe 10 and shoe positioning means including a sole rest shiftable into a plurality of operative positions, a latch and a latch lifting device

which is operatively connected with the latch and with the rest with provision for freeing the latch and thereafter shifting 15 the rest during continued movement of said device.

In testimony whereof I have signed my name to this specification in the presence of two subscribing witnesses.

CHARLES DE MINICO.
